UNITED STATES PATENT OFFICE.

ZACHARIAH E. HOUSE, OF CASS LAKE, MINNESOTA.

TOY CANNON.

1,141,710.

Specification of Letters Patent. Patented June 1, 1915.

Application filed January 28, 1915. Serial No. 4,869.

To all whom it may concern:

Be it known that I, ZACHARIAH E. HOUSE, a citizen of the United States, and a resident of Cass Lake, in the county of Cass and State of Minnesota, have invented a new and useful Improvement in Toy Cannons, of which the following is a specification.

My invention has for its object to provide a device of the character specified, so constructed and arranged that it will explode a paper fulminate cap, and will utilize the products of the explosion to project a ball of cotton, paper or like light materials.

In the drawings:—Figure 1 is a longitudinal vertical section of the improved cannon, Fig. 2 is a transverse section, Fig. 3 is an enlarged sectional detail of the exploding mechanism, and Fig. 4 is a perspective view of the firing pin supporting cap and the paper cap support detached.

The present embodiment of the invention comprises a barrel or body consisting of an outer casing composed of three integral portions, and an inner casing held at the axis 25 of the outer casing. The outer casing or shell consists of a cylindrical body 1, having at one end a frusto-conical extension 2 and at the other end a cap or cover 3, which is hinged to the body at the lower side thereof 30 as indicated at 4.

A resilient latch 5 is connected to the cap or cover at the upper side thereof, and this latch has a catch which is adapted to engage an opening 6 in the outer casing to hold the 35 cover to the casing, and an incline 6^a, co-operates with the lower beveled end of the cap to lift the latch to permit it to enter the opening.

A transverse partition or diaphragm 7 is 40 arranged within the body near the end adjacent to the cap, and the inner casing 8, which is the barrel or bore of the gun, is supported by the diaphragm 7 and by a diaphragm 9 at the outer or small end of the frusto-conical portion. The barrel or bore 8 is cylindrical in form and the outer end is flush with the outer end of the diaphragm 9, while the inner end extends through the diaphragm 7.

45 The outer end of the barrel is open but the inner end is closed with a cap 10, the said cap fitting over the inner end of the barrel, and having a central opening 11, in which is arranged the firing pin 12, the pin 50 being rigidly connected to the cap. The firing pin extends through the cap at both

sides thereof, and the cap or cover is provided with a cylinder 13, of the same diameter as the barrel or bore, and held coaxial with the barrel or bore when the cap or 60 cover is closed.

It will be noted from an inspection of Fig. 1 that the cap or cover is the segment of a sphere, and the cap or cover has also a tubular extension 14, which extends downwardly from the cylinder 13 near the inner end thereof. A transverse plate 15 supports the inner end of the cylinder 13, the ends of the plate being connected to the cap, and the cap extends far enough beyond the inner end 70 of the barrel or bore 8 to bring the closed end thereof near to the inner end of the cylinder 13 and to bring the firing pin 12 within the inner end of the said cylinder.

A plunger 16 is arranged within the cylinder 13, and the plunger is normally forced 75 toward the firing pin by a coil spring 17. A rod 18 is passed through a central opening in the cap or cover 3 and through a central opening in the plunger and the rod has a head 19 on the inner side of the plunger.

The outer end of the rod is provided with a hook 21 for convenience in manipulating the same, and a latch 22 is mounted to slide in the tubular extension 14, the inner end of the latch passing through an opening in the under side of the cylinder 13 to engage in front of the plunger 16 to prevent movement thereof toward the driving pin. The latch 22 has a stop 24 in the form of a collar 80 within the extension 14, and a coil spring 25 is arranged between the stop 24 and stops 26 in the form of struck up lugs in the interior of the extension. The spring acts normally to press the latch into engaging position, 85 and a handle or grip 27 is connected to the latch and extends through the cap or cover 90 3 to permit the latch to be moved downwardly to release the plunger.

A tubular casing 28 is arranged within the 100 barrel or bore at the end adjacent to the cap, and the casing is supported a little higher at its inner end than at its outer end, by means of a strip 29 of metal held to the barrel or bore and extending into the cap 105 110 and having an up-turned lug 30 within the cap. The casing 28 has lugs 31 at each side extending longitudinally from the casing toward the cap, and the paper cap indicated at 32 is held by the lug 30 and the lugs 31 against that end of the firing pin 12, which is within the cap.

The front end of the casing 28 rests upon the bottom of the barrel or bore, and the projectile shown at 33 is arranged against the said end of the casing. Since the casing 28 is closed except at its ends, and the cap 10 is fluid tight, the expanding products of the explosion of the cap will be compelled to move outwardly through the barrel or bore 8, and the said products of the explosion will 10 carry the projectile out of the barrel.

The operation of the gun proper is as follows:—To load the gun, the cap or cover 3 is released from the body by means of the latch 5, and the said cap or cover is swung 15 down into the dotted line position of Fig. 1. The cap 10 is then removed after which the fulminate cap is placed in position supported by the lugs 30—31. The cap 10 is then replaced, and the cover is closed. By 20 means of the hook 21 the plunger 16 is drawn outwardly and as soon as the plunger passes beyond the latch 22, the spring 25 will force the latch upward to lock the plunger 16 with the spring 17 under tension.

To fire the cannon, the handle 27 of the latch is pulled downwardly, pulling the latch downwardly and releasing the plunger. The spring 17 immediately forces the plunger toward the firing pin and the cap is exploded by the firing pin when the plunger strikes the pin. The products of the explosion expanding drive the projectile 33 outward at the open end of the cannon.

The improved cannon is supported by 35 wheels 34, the said wheels being secured to the ends of an axle 35, the said axle being tubular in the present instance. The tubular axle is journaled in bearing sleeves 36, which are secured to the under sides of ammunition 40 cases or boxes 37, the said boxes being spaced apart from each other laterally to receive the outer casing of the gun between them.

Each case has a cover 38, and the covers are hinged to the cases at the outer sides of 45 the cases as indicated at 39 to permit the covers to be opened outwardly into the dotted line position of Fig. 2. The gun is mounted between the ammunition boxes, the outer casing being provided with trunnions 50 or journal pins 40, which are received in openings in the inner sides of the ammunition cases.

The gun is free to swing on the journal pins 40, and it is held in adjusted position 55 as regards elevation, by means of a rack bar 41. The rack bar is approximately semi-circular in cross section, and the side edges thereof are notched as shown at 42. The rack bar is pivoted to the gun by means of a 60 bail 43, the bail passing through an opening in the rack bar at the upper end thereof and having its ends secured to the outer casing of the gun in any desired manner as for instance, by soldering. The lower end 65 of the rack bar passes through a slot or

opening 44 in the body 45 of a trail, the said trail consisting of the body 45 and depending flanges 46.

The body of the trail decreases in width rearwardly and at the rear end of the trail 70 a wheel 47 is arranged between the flanges, the wheel being secured to an axle 48 which is journaled in openings in the flanges. The trail consists of two portions arranged at an obtuse angle with respect to each other, 75 and the upper portion extends between the ammunition cases and is secured to the said cases. The trail is rigid with the ammunition cases, and the rack bar is pressed in a direction to cause the notches 42 thereof to 80 engage the rear wall of the slot 45 by means of a spring 49, secured to the under face of the body of the trail.

To adjust the gun as regards elevation, the rack bar is pressed forwardly at its lower 85 end to release the notches from the side wall of the slot. When this has been done the rear end of the gun may be swung upward or downward and when the rack bar is released it will hold the gun at the desired 90 elevation.

In order to permit the assembling or disassembling of the gun one or both of the wheels is made removable from the axle. When it is required to take the gun apart, 95 the removable wheel is removed, and the axle is withdrawn from the bearing sleeves 36 of the ammunition cases. The cases may be now pulled apart to release the gun, after the gun has been released from the trail by 100 withdrawing the rack bar.

The flanges 46 of the trail have notches 50 fitting over the axle, and these notches prevent movement of the axle longitudinally of the trail. The trail cannot move upward 105 when in place because of the ammunition cases. The hook is formed and while yet straight is engaged with the opening of the plunger 16, and the head 19 is countersunk at the inner end of the plunger. The rod 110 engages the plunger and is held tightly in connection therewith by friction. After the rod has been passed through the opening in the cap the hook 21 is formed.

I claim:—

1. A device of the character specified, comprising an inner cylindrical casing and an outer inclosing casing, said casings being flush at one end and being connected at the said end, a rigid support between the casings near the opposite end, a fluid tight cap engaging the said other end of the inner casing, a cap or cover hinged to the outer casing at the rear end to open downwardly, latch mechanism for holding the cover closed, a support rigidly fixed within the inner casing at the cap, and having means at the end adjacent to the cap for supporting a paper firing cap at the inner end of the firing pin and in contact with the pin, 115 120 125 130 135

- the barrel being adapted to receive a projectile at the outer end of the said support, the cap having a cylinder coaxial with the inner casing when the cap is closed, a spring 5 pressed plunger within the cylinder for engaging the firing pin, means for retracting the plunger, and a releasable latch for holding the plunger in set position, the cap of the inner casing being removable with the 10 firing pin to permit the insertion of the explosive cap, oppositely arranged ammunition cases having bearing openings in their adjacent walls, the outer casing of the gun having oppositely extending journal pins 15 for engaging the openings to pivotally support the gun, said ammunition cases having registering transverse bearing sleeves on their under sides, an axle passing through the sleeves and provided at its ends with 20 wheels outside of the ammunition cases, a trail between the ammunition cases and having means for engaging over the axle and provided at its rear end with a wheel, a rack bar pivoted to the gun near the cap or cover 25 and extending through an opening in the trail, and a spring pressing the rack bar into engagement with the opening to hold the gun in adjusted position.
2. A device of the character specified, comprising an inner cylindrical casing and an outer inclosing casing, said casings being flush at one end and being connected at the said end, a rigid support between the casings near the opposite end, a fluid tight cap 30 engaging the said other end of the inner casing, a cap or cover hinged to the outer casing at the said end to open downwardly, latch mechanism for holding the cover closed, a support rigidly fixed within the inner casing 35 at the cap, and having means at the end adjacent to the cap for supporting a paper fulminate cap at the inner end of the firing pin and in contact with the pin, the barrel being adapted to receive a projectile at the 40 outer end of the said support, the cap having a cylinder coaxial with the inner casing when the cap is closed, a spring pressed plunger within the cylinder for engaging the firing pin, means for withdrawing the 45 plunger, and a releasable latch for holding the plunger in set position, the cap of the inner casing being removable with the firing pin to permit the insertion of the explosive cap.
5. A device of the character specified, comprising an inner cylindrical casing and an outer inclosing casing, said casings being flush at one end and being connected at the said end, a rigid support between the casings near the opposite end, a fluid tight cap 50 engaging the said other end of the inner casing, a cap or cover hinged to the outer casing at the said end to open downwardly, latch mechanism for holding the cover closed, a support rigidly fixed within the inner casing 55 at the cap, and having means at the end adjacent to the cap for supporting a paper fulminate cap at the inner end of the firing pin and in contact with the pin, the barrel being adapted to receive a projectile at the outer end of the said support, the cap having a cylinder coaxial with the inner casing when the cap is closed, a spring pressed plunger within the cylinder for engaging the firing pin, means for withdrawing the plunger, and a releasable latch for holding the plunger in set position, the cap of the inner casing being removable with the firing pin to permit the insertion of the explosive cap.
6. A device of the character specified, comprising an inner cylindrical casing and an outer inclosing casing, said casings being flush at one end and being connected at the said end, a rigid support between the casings near the opposite end, a fluid tight cap 60 engaging the said other end of the inner casing, a cap or cover hinged to the outer casing at the said end to open downwardly, latch mechanism for holding the cover closed, a support rigidly fixed within the inner casing 65 at the cap, and having means at the end adjacent to the cap for supporting a paper fulminate cap at the inner end of the firing pin and in contact with the pin, the barrel being adapted to receive a projectile at the outer end of the said support, the cap having a cylinder coaxial with the inner casing when the cap is closed, a spring pressed plunger within the cylinder for engaging the firing pin, means for retracting the plunger, and a releasable latch for holding the plunger in set position, the cap of the inner casing being removable with the firing pin to permit the insertion of the explosive cap.
7. A toy cannon, comprising a barrel, a 70 inner casing at the cap, and having means at the end adjacent to the cap for supporting a paper fulminate cap at the inner end of the firing pin and in contact with the pin, the barrel being adapted to receive a projectile at the outer end of the said support, a spring actuated striker supported by the cap or cover for engaging the outer end of the firing pin to explode the cap, and releasable means for restraining the operation 75 of the striker.
4. A device of the character specified, comprising an inner cylindrical casing and an outer inclosing casing, said casings being flush at one end and being connected at the 80 said end, a rigid support between the casings near the opposite end, a fluid tight cap engaging the said other end of the inner casing, a cap or cover hinged to the outer casing at the said end to open downwardly, a latch mechanism for holding the cover closed, a support rigidly fixed within the inner casing at the cap, and having means at the end adjacent to the cap for supporting a paper fulminate cap at the inner end of the 85 firing pin and in contact with the pin, the barrel being adapted to receive a projectile at the outer end of the said support, and striking mechanism carried by the cap for engaging the pin to explode the cap.
5. In a device of the character specified, the combination with the barrel having at one end a detachable cap provided with an axial firing pin, an inclosing casing for the barrel, the end of the barrel remote from the cap opening through the adjacent end of the casing, said casing having a cover at the end adjacent to the cap and inclosing the cap, said cover having a spring controlled striker for striking the firing pin, and having a releasable latch for restraining the operation of the striker, and means within the barrel for supporting a paper explosive cap for contact with the inner end of the firing pin, said means comprising a 90 block or rod having lugs for supporting the cap in upright position, and adapted to limit the inward movement of a projectile at the other end.
6. In a device of the character specified, the combination with the barrel having at one end a detachable cap provided with an axial firing pin, an inclosing casing for the barrel, the end of the barrel remote from the cap opening through the adjacent end of the casing, said casing having a cover at the end adjacent to the cap and inclosing the cap, said cover having a spring controlled striker for striking the firing pin, and having a releasable latch for restraining the 95 operation of the striker, and means within the barrel for supporting a paper explosive cap in contact with the inner end of the firing pin.
7. A toy cannon, comprising a barrel, a 100 inner casing at the cap, and having means at the end adjacent to the cap for supporting a paper fulminate cap at the inner end of the firing pin and in contact with the pin, the barrel being adapted to receive a projectile at the outer end of the said support, a spring actuated striker supported by the cap or cover for engaging the outer end of the firing pin to explode the cap, and releasable means for restraining the operation 105 of the striker.
8. In a device of the character specified, the combination with the barrel having at one end a detachable cap provided with an axial firing pin, an inclosing casing for the barrel, the end of the barrel remote from the cap opening through the adjacent end of the casing, said casing having a cover at the end adjacent to the cap and inclosing the cap, said cover having a spring controlled striker for striking the firing pin, and having a releasable latch for restraining the 110 operation of the striker, and means within the barrel for supporting a paper explosive cap in contact with the inner end of the firing pin.
9. In a device of the character specified, the combination with the barrel having at one end a detachable cap provided with an axial firing pin, an inclosing casing for the barrel, the end of the barrel remote from the cap opening through the adjacent end of the casing, said casing having a cover at the end adjacent to the cap and inclosing the cap, said cover having a spring controlled striker for striking the firing pin, and having a releasable latch for restraining the 115 operation of the striker, and means within the barrel for supporting a paper explosive cap in contact with the inner end of the firing pin.
10. In a device of the character specified, the combination with the barrel having at one end a detachable cap provided with an axial firing pin, an inclosing casing for the barrel, the end of the barrel remote from the cap opening through the adjacent end of the casing, said casing having a cover at the end adjacent to the cap and inclosing the cap, said cover having a spring controlled striker for striking the firing pin, and having a releasable latch for restraining the 120 operation of the striker, and means within the barrel for supporting a paper explosive cap in contact with the inner end of the firing pin.
11. In a device of the character specified, the combination with the barrel having at one end a detachable cap provided with an axial firing pin, an inclosing casing for the barrel, the end of the barrel remote from the cap opening through the adjacent end of the casing, said casing having a cover at the end adjacent to the cap and inclosing the cap, said cover having a spring controlled striker for striking the firing pin, and having a releasable latch for restraining the 125 operation of the striker, and means within the barrel for supporting a paper explosive cap in contact with the inner end of the firing pin.

trail provided with a pair of laterally spaced ammunition cases, each case having on the under face thereof a bearing sleeve, and the sleeves being in alinement, and an 5 axle passing through the sleeves and provided with wheels at its ends, and means in connection with the barrel and the trail

for permitting the barrel to be adjusted with respect to the trail.
